(57) **CLAIM**

The ornamental design for a portable image projection system, as shown and described.

DESCRIPTION

FIG. 1 is a right side, front perspective view of a portable image projection system showing my new design;

FIG. 2 is a right side, rear perspective view thereof;

FIG. 3 is a left side, rear perspective view thereof;

FIGS. 4 and 5 are respective front and rear side elevation views thereof;

FIGS. 6 and 7 are respective top and bottom plan views thereof; and,

FIGS. 8 and 9 are respective right and left side elevation views thereof.

The broken lines are shown to illustrate the environment only and form no part of the claimed design.
